UNITED STATES PATENT OFFICE

97,300

DESIGN FOR A STAND FOR A HAMMOCK OR SIMILAR ARTICLE

William A. Moeller, Los Angeles, Calif.

Application August 5, 1935, Serial No. 57,962

Term of patent 14 years

To all whom it may concern:

Be it known that I, William A. Moeller, a citizen of the United States, residing at Los Angeles, in the county of Los Angeles and State of California, have invented a new, original, and ornamental Design for a Stand for a Hammock or Similar Article, of which the following is a specification, reference being had to the accompanying drawing, forming part thereof.

The figure is a perspective view of the stand showing my design.

I claim:

The ornamental design for a stand for a hammock or similar article as shown.

WILLIAM A. MOELLER.
